TOOL FOR COMPRESSING AND CLAMPING SPRINGS

Filed March 20, 1922

Inventor

W. W. PRYMEK.

By *W. W. PRYMEK*

Attorneys

UNITED STATES PATENT OFFICE.

WALTER W. PRYMEK, OF IOWA CITY, IOWA.

TOOL FOR COMPRESSING AND CLAMPING SPRINGS.

Application filed March 20, 1922. Serial No. 545,201.

To all whom it may concern:

Be it known that I, WALTER W. PRYMEK, a citizen of the United States, and resident of Iowa City, in the county of Johnson and State of Iowa, have invented certain new and useful Improvements in Tools for Compressing and Clamping Springs; and I do hereby declare the following to be a full, clear, and exact description of the invention, such as will enable others skilled in the art to which it appertains to make and use the same.

My invention relates to tools for compressing and clamping springs such as are used with valves of gas engines, and the object of my invention is to produce a simple and efficient device of this character with the parts so arranged that there is no likelihood of any element becoming detached and lost, and which can be conveniently carried in a tool chest and used on all types of motors, overhead, L- or T type, the device being adapted for free and clear movement without interference by projections of the engine, and effective to produce a quick compression and release of the spring.

In the drawings, Figure 1 is a view in side elevation of my improved spring compressor and clamp. Figure 2 is a top plan view. Figure 3 is a view similar to Figure 1 showing a spring compressed and clamped. Figure 4 is a front elevation.

My improved spring compressor and clamp includes a base or relatively fixed member A having a horizontally disposed bifurcated portion 1 and a slotted post 2, a removable block B being secured to the post for a sliding movement thereon by a screw passed through the slot of the post. This movable block is recessed to form a supporting ledge for a pair of fingers C which cooperate with the bifurcated portion 1 to clamp a spring. Each of the fingers is separately formed and has a flat portion 4 and an extension which is outwardly and upwardly curved and terminates in a crook 5. The flat portion of each finger is designed for overlapping engagement with the similarly formed portion of its fellow finger, these overlapping portions having slots 6 through which project a threaded rod 7 supported by the bifurcated portion 1. The slots 6 permit the fingers being spread apart to accommodate themselves to springs of various widths. This spreading movement is in a straight line, the edges 8 of the fingers

lying next to the block B acting, in connection with the contiguous wall of such block, to prevent any turning movement of the fingers and thus any accidental dislodgment of the crooked end of the fingers from a compressed spring.

The operation of my improved clamp will be readily apparent. With the block B moved to its uppermost point on the post 2, a spring may be readily engaged, the bifurcated portion 1 taking under the spring, including spring washer if desired, and the crooked ends of the fingers engaging the uppermost coil at each side. Turning of a nut 10 will then draw the block down toward the bifurcated portion and thus compress the spring. When fully compressed the parts may be locked in this position by the thumb nut 12. The upward curvature of the fingers permits their ready insertion in the motor and this is effective to greater ease in manipulating the device in assembling and dismantling. It is to be noted that by the adjustment which may be had of the fingers springs of various widths may be accommodated, and the forks of the bifurcated portion of the base are sufficiently spaced to accommodate the device to a wide range in the size of springs.

I claim as my invention:

1. A spring compressor including a bifurcated base having a lateral extension, a member slidably on said lateral extension, a pair of fingers slidably laterally on said member, and means for sliding the member on the lateral extension disposed between said extension and the spring engaging portions of the base and fingers adapted to compress a spring between the base and fingers when said parts are moved toward each other.

2. A spring compressor including a bifurcated base having a lateral extension, a block slidably mounted on said extension and having a cut away portion forming a transverse shoulder across the upper portion of the block, a pair of spring engaging fingers slidably mounted on the block having portions engaging said shoulder to prevent a turning movement of said fingers on the block and means for sliding the block on said extension adapted to compress and hold a spring between the fingers and base when the block is moved toward the base.

3. A device of the character described including a bifurcated base, a longitudinally

slotted post secured to said base and disposed at right angles thereto, a supporting member in sliding engagement with said post and connected thereto through said slot, a 5 pair of separable fingers carried by said supporting member, means preventing a turning movement of said fingers on said supporting member, and means for varying the position of said supporting member relative to said post, said means controlling the position of said fingers each to the other.

4. A device of the character described including a bifurcated base, a longitudinally slotted post secured to said base and disposed at right angles thereto, a supporting member in sliding engagement with said post and connected thereto through said slot, a pair of separable fingers carried by said supporting member and each having a 15 slot, means preventing turning movement of said fingers on said supporting member, and means in part carried by said post and extending through the slots of said fingers for varying the position of said supporting member relative to said post, said means controlling the position of said fingers each to the other.

5. A device of the character described including a bifurcated base, a post disposed

at right angles to said base, said post having a longitudinal slot, a block in sliding engagement with said post and connected thereto through said slot, said block having a supporting ledge, a pair of separable fingers carried on said supporting ledge, each 35 of said fingers having a slot and a straight edge, the straight edge being adapted for engagement with said block to prevent turning movement of its finger on said block, and a bolt and nut for varying the position 40 of said block on said base and controlling the position of said fingers each to the other, said bolt extending through the ledge of said block and the slots of said fingers.

6. A spring compressor including a bifurcated base having a lateral extension, a block slidably mounted on said extension having spring engaging fingers provided with upwardly extended engaging terminals, and means positioned between said 45 lateral extension and the spring engaging terminals of said fingers and base adapted for moving the block and fingers toward the base for compressing and holding a spring therebetween.

In testimony whereof I have signed this specification.

WALTER W. PRYMEK.
